UNITED STATES PATENT OFFICE.

JOHN BIGELOW, OF PHILADELPHIA, PENNSYLVANIA.

MACHINE FOR SEWING AND TRIMMING FABRICS.

SPECIFICATION forming part of Letters Patent No. 244,531, dated July 19, 1881.

Application filed August 19, 1880. (Model.)

To all whom it may concern:

Be it known that I, JOHN BIGELOW, a citizen of the United States, residing at Philadelphia, in the county of Philadelphia and State of Pennsylvania, have invented certain new and useful Improvements in Zigzag or Irregular Stitch Sewing Machines with Trimming Devices; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the accompanying drawings similar letters of reference indicate like parts.

Figure 1 is a perspective of a device embodying my invention. Fig. 2 is a perspective, showing the needle-throat with its tongue and its relation to the feed. Fig. 3 is a top view of the presser-foot, showing its needle-throat, its horn-projection, and the relation of the projection to the cutting-point of the trimming device. Fig. 4 is a front elevation of the presser-foot.

The object of the present invention is to produce a combination of mechanism adapted, among other things, to make the "cut-hose" patented in reissue Letters Patent No. 9,113, dated March 9, 1880. The device is particularly applicable to the mechanism shown in reissue Letters Patent No. 9,112, dated March 9, 1880; and it consists in so arranging the trimming device that instead of being attached to and carried by the reciprocating work-plate, as in that patent, it shall swing on a pivot or center behind said reciprocating plate, from which, however, it receives its swinging movement in such a manner that the cutting-point of the shears will follow the sewing-point of the material as it is being moved for making a zigzag stitch. The modification, as shown, extends also to the presser-foot, which is stationary, and to the needle-throat, which, instead of being a simple slot at right angles to the line of sewing, consists of a slot with a tongue, C', over which the stitch is made parallel with said line, but so placed and arranged that the alternate reciprocations of the plate to which it is attached will place it first on one and then on the other side of the point of perforation of the needle. The trim-

ming device is, however, equally applicable to the needle-throat and vibrating presser-foot described in said patent.

The construction and operation of the machine are as follows, viz., using the reciprocating plate, the sewing and the shear-actuating mechanism described in my said patent No. 9,112: At a point, G, behind the reciprocating plate B, and a little to the left of the line of the needle, I pivot the plate D, to which the shear-blades are attached. The plate D has a slotted connection with a pin, F, in the cap E, which cap is adjustably attached to the plate B. The pin F is so set that the points of the shears will move in harmony with the plate where they touch the same near the needle-throat, Fig. 3. The plate B, by mechanism described in said patent No. 9,112, at each stitch reciprocates alternately to the right and left and at right angles to the line of feed. By placing the pin K in the vertical actuating trimmer-bar L, described in said patent, back at a point central or nearly so over the knife-plate pivot G, it can be connected with the upper shear-blade, to which it conveys motion at a point where said blade has little or no lateral movement, and with the plate D, securely held by the pivot-pin G and cap E, all of the practical advantages of a stationary shear-plate are gained.

A further improvement is that with the reciprocating plate B and swinging shear-plate D, I have added a throat-plate, C, having a tongue-piece, C', Fig. 2, and a stationary presser-foot. The tongue-piece C' is attached to the plate C, which, in turn, is screwed to the reciprocating plate B, and so arranged that the needle will pass down alternately on one side of said tongue-piece and then the other in making its stitches. The stitches are thus made over the tongue, which is tapered to the point, so they will readily pass from it as the work is fed along. As the feed is only on one side of the needle-throat, and the friction of the stationary presser-foot against the lateral movement of the work has to be overcome, the stitch thus formed around the tongue, which is reciprocated by the plate B, assists the material at the point of sewing to reciprocate to the right and left, and causes the stitching to be zigzag or irregular.

The device above described is one of the

modifications of a tongue vibrated above and across the needle-throat of a sewing-machine, for which I have made application for patent, as shown in cases 15,651 and 15,669, filed

5 August 19, 1880.

The presser-foot M has a horn or projection, M', on its right side as the operator looks toward it, when on the machine. It extends considerably to one side of the line of perforation 10 of the sewing-needle, and also beyond the cutting-front of the trimming device. It serves a double purpose—keeping the work down where perforated by the needle, thus, with shuttle-machines, insuring the taking of its loop by the shuttle, and, also, in material having edges liable to curl or roll up on itself, it serves to keep such curl or roll from interfering with the cutting or trimming device, as explained and claimed in my reissue Letters Patent No. 9,112. This horn differs from the one shown in said Letters Patent, however, in that it surrounds the needle and is finely slotted at its rear to admit of the ends of the needle-thread being passed through when starting to 25 sew.

What I claim as new, and desire to secure by Letters Patent, is—

1. In combination with the work-plate of a sewing-machine reciprocated at right angles to the line of feed, a shear trimmer-plate pivoted at a stationary point behind said reciprocating work-plate, and receiving a vibrating motion from the same, substantially as and for the purpose described.

2. The combination of a swinging shear-trimming device, a needle throat-plate having a tongue reciprocated at right angles to the line of feed, and a stationary presser-foot, substantially as and for the purpose described.

3. In combination with the stitch-forming mechanism of a sewing-machine for making a zigzag or irregular stitch by alternate lateral movement of the material being sewed, a shear-trimmer and devices for causing the cutting-point to follow the vibration of the material while the point at which its upper blade is actuated is nearly or quite stationary, substantially as described.

In testimony whereof I affix my signature in presence of two witnesses.

JOHN BIGELOW.

Witnesses:

L. DEANE,

G. W. BALLOCH.
